UNITED STATES PATENT OFFICE

RALPH A. CHAMBERLIN, OF FONDA, IOWA

SPARK CONTROL FOR INTERNAL COMBUSTION ENGINES

Application filed May 27, 1929, Serial No. 366,493. Renewed April 6, 1931.

My invention relates to spark control in internal combustion engines, and has for its object to provide a semi-automatic control, adapted to effect retardation of the spark when the engine is being started.

The effectiveness of the device of my invention depends upon the fact that it is almost always necessary to choke the carburetor of an internal combustion engine during starting. Most motorists, even in the hottest days of summer, use the choke, from force of habit if from no other cause. My invention takes advantage of this fact by connecting the carburetor with the control rod or some portion of the normal control of the timer or distributor in such a manner that during the choking process, the spark control will be actuated to retard the spark.

A further object of my invention is to provide a device that may be adapted to any internal combustion engine, for transferring the movement of the choke lever to the spark control.

A further object is to provide a device of this kind that is simple, durable, and inexpensive in construction.

With these and other objects in view, my invention consists in the construction, arrangement, and combination of the various parts of my device, whereby the objects contemplated are attained, as hereinafter more fully set forth, pointed out in my claim, and illustrated in the accompanying drawings, in which:

Fig. 1 is a plan view of an engine to which my invention is attached,

Fig. 2 is a plan view in detail of the transfer device.

Fig. 3 is a similar view with the top plate of the device removed, and

Fig. 4 is a detail sectional view through the device.

I have used the reference character 10 to indicate generally the body of an internal combustion engine having the carburetor 11, the choke lever with the two arms 12 and 13, the spark control rod 14, and the timer 15.

The transfer device comprises a base plate 16, provided with a pair of openings through which are extended bolts 17, a top plate 18,

through which the bolts 17 also pass, and a pair of sleeves 19, through which the bolts pass, and which serve to space the top plate 18 from the base plate 16.

Nuts 20 are threaded onto the bolts 17, and hold the top plate 18 securely in place.

Freely rotatable on the sleeves 19 are a pair of pinions 21, meshing with each other.

The pinions 21 are provided with polygonal shoulders 22, upon which are loosely fitted the sockets 23 of levers 24 and 25.

A rod 26 is provided, to connect the lever 25 with the arm 12 of the choke lever, and a rod 27 is provided, to connect the lever 24 with the spark control rod 14.

The rod 27 is provided with a loop 28, which encircles the rod 14, and is slidable thereon. Engagement of the loop 28 with the rod 14 is effected by means of a collar 29, secured to the rod 14.

In the arrangement shown, when the operator pulls upwardly on the choke rod 30, the arm 12 will move rearwardly, as indicated by the arrow 31.

This will cause the arm 25 of the transfer device to move as indicated by the arrow 32 in Fig. 3, and the lever 24 of the transfer device will be swung, due to the meshing of the pinions 21, in the direction indicated by the arrow 33, moving the rod 27 in the direction 80 indicated by the arrow 34 in Fig. 1, and pushing the spark rod 14 in the same direction.

When the spark control is actuated in the usual way by the hand lever on the steering wheel of the vehicle, the rod 14 will slide 85 through the loop 28, as will be evident from the drawings.

It will be understood that many different arrangements will be encountered in the relative positions of spark control rods and choke levers, and for this reason, it is desirable that the transfer device be adaptable to adjustment. For instance, if the choke lever were such that the rod 26 could only 90 be connected for movement in a direction opposite to that of the arrow 31 in Fig. 1, while the rod 14 were adapted to movement in the same direction as hereinbefore described, then the proper movement could be transferred 95 100.

by shifting the lever 24 to a position at 180 degrees from the position shown.

This is done by removing the top plate 18, lifting the lever to its new position, and re-

5 placing the top plate.

The device is installed on a bracket, made to fit the particular engine to which the device is attached, such as the bracket 35 shown, by means of the extension 36 of the base plate

10 16. A pair of securing elements are em- ployed for this purpose, such as the bolts 37.

In the particular installation shown, the bracket 35 is attached to a convenient bolt on the engine, and a brace 40 extends from one 15 of the bolts 37 to one of the manifold clamp bolts 41 of the particular engine shown.

Some changes may be made in the construction and arrangement of the various parts of my invention without departing from the 20 true spirit of the invention, and it is my intention to cover by my claim, any modified form or the use of mechanical equivalents of the invention that may be reasonably includ- ed within their scope.

25 I claim as my invention:

A device of the class described, comprising a pair of plates, bolts extended through said plates and holding them together, sleeves sur- 30 rounding said bolts and engaging the inner faces of the plates to hold them apart, a pair of pinions journaled on said sleeves and mesh- ing with each other, said pinions having poly- 35 gonal shoulders, and a pair of levers pro- vided with sockets received upon said shoul- ders, said levers being held in place by one of the plates.

Signed this 24th day of May, 1929, in the city of Fonda and State of Iowa.

RALPH A. CHAMBERLIN.
